UNITED STATES PATENT OFFICE

HARRISON J. L. FRANK, OF DETROIT, MICHIGAN, ASSIGNOR TO BULLDOG ELECTRIC PRODUCTS COMPANY, OF DETROIT, MICHIGAN, A CORPORATION OF WEST VIRGINIA

METERING PANEL

Application filed March 13, 1929. Serial No. 346,637.

The present invention relates to electrical devices and especially to metering panels.

Among the objects of the invention is a metering or switching panel built up of small identical replaceable units in which the "live" parts are all so arranged that it is substantially impossible for an attendant or other person to touch them accidentally.

Another object of this invention is to provide a switching and metering unit that may be combined with other similar units so that a door or cover may be provided over the switching section, preventing access to same by unqualified persons, yet allowing the fuses to be accessible for easy replacement.

Another object is a panel in which rearrangement of the circuits may be accomplished with a minimum of time and effort and a maximum of safety.

Another object of the invention is a design of a metering panel unit that may be assembled with like units or switching sections, these units being designed to be co-ordinated with other similar units containing switches and fuses, fuses only, and main fuses, for the purpose of combining any quantity and number of these units in combination, to meet any desired condition required of a metering and switching panel.

Still other objects will readily appear to those skilled in the art upon reference to the following description and the accompanying drawings in which

Fig. 1 is a plan view of one of the units; Fig. 2 is a partly sectional side elevation on the line 2—2 of Fig. 1; Fig. 2a is a view of the underside of two of the units showing one method of use; Fig. 3 is a partly sectional longitudinal view of a modified form; Fig. 4 is a partial cross section showing the bus bars and one of the connecting clips; Fig. 5 is a plan showing the guards used in the form of device of Fig. 3; and Fig. 6 is an elevation of a metering panel indicating one use of the switching units.

As indicated each unit of the panel comprises an insulating block 10, having fuse sockets 11 at each end thereof, and having the latter somewhat higher than the mid-

portion so that the latter may be covered if desired with a suitable sealing means leaving the former accessible, it being understood that the fuse sockets may be of any type such as cartridge or plug fuse.

This mid portion is provided with two sets of narrow and comparatively deep cross grooves 15 one set on each side of the center line of the block, while across the center is a raised portion 16 provided with cylindrical cups or depressions 17 having bolt holes therein extending through the block to grooves 18 on the underside.

These grooves 18 are longitudinal of the block and each extends from beneath a cup 17 to beneath a fuse socket 11. The blocks 10 are also provided with suitable holes for the passage of fastening screws 20 by means of which they may be secured to a suitable support 21 which may be and usually is the back wall of a metal cabinet. The grooves 15 and 18 are each intended for the reception of bus bars as shown.

In the grooves 15 bus bars 30 lie on edge and are of such width that they lie below the surface of the block and may extend across several blocks 10 placed in alignment and panels of any desired number of blocks so made up. At the ends of such a panel or single block 10, is placed a member 19 preferably a rectangular block of insulating material whose upper surface is in alignment with the bottoms of the grooves 15. The bars 30 are secured in place thereon by strips 31 of insulating material notched or grooved as indicated and fastened over the bars upon members 19 by screws 32. Bars 30 are shown as having their ends 33 twisted a quarter turn to facilitate their electrical connection.

The grooves 18 are designed to receive short bus bars 35 each secured at one end to the central contact of a fuse, this contact being in the present instance represented by the screw 36 extending from the socket 11 through the bottom thereof into the bar 35.

The other end of each bar 35 underlies a cup 17 and is secured by a bolt or screw 37 extending up through the block into the cup and is screwed into a cap 38 having perfo-

rated ears 39 between which are hinged a bar 40 which is of sufficient length to span either group of bus bars 30. The bar 40 is preferably circular in section and carries a slideable contact member 41 and also an insulating shield 42. This contact member consists of a short sleeve 45 slotted to receive the bar 40 and provided with a set screw 46 having preferably an insulating head thereon, whereby the sleeve may be fixed in position longitudinally of the bar 40. This sleeve also carries spring fingers 47 adapted to enter one of the grooves 15 and contact with the bus bar 30 therein. Slots 15a being provided for this purpose. The shield 42 consists of two side strips 50 of insulating material secured to two end pieces 51 rotatably mounted on the bar 40.

This arrangement of bar 40 and its contact member 41 and shield 42 permits its use upon any bus bar 30 of either group.

In Fig. 2a the underside of two of the units 10 is shown indicating how several of the meter circuits may be connected together and to one of the bars 30 as by securing a connecting bar 35b to the undersides of the fuse sockets or the screws 36.

In the form of device shown in Fig. 3, the base portion 10a may be the same as the base portion 10 with the bus bars 30 and 35 and fuse sockets similarly mounted therein except that instead of screws 37 passing up into caps 38, screws 60 pass through the ends of bars 35 and into threaded sleeves 61 fitting into the passages 62 passing up through the block 10a on its central line. These sleeves 61 at their upper ends have soldered or otherwise secured to them, insulated cables 63 with the insulation extending into passages 62.

Each cable 63 is long enough to reach to the outermost bar 30 and terminates in a plug 64 of insulating material having spring contact fingers 65 passing therethrough and connected to the conductor in the cable. These fingers 65, like fingers 47, are adapted to enter grooves 15 to contact with the bars 30.

In this form of the device the free ends of plugs 64 on the cables are held in place by means of the wire guards shown at 70 in Figs. 3 and 5. These guards 70 consist as shown of loops of wire hinged at one end, as at 71, to the fuse socket containing portion 55 of the block and secured at the other end by releasable means 72 such as a screw or rotatable catch bolt. The loops are of sufficient width to pass the cable 63 but not the plug 64 so that, when the plug is in contact position, the loops lock it in place. Likewise, when it is not desired to make a contact, the plug may be laid on its side as shown at 64a, Fig. 3, and the loop 70 retains it in this position.

65 It is proposed to use in this form of the

device, differently colored cables 63 with correspondingly colored markers on the fuse sockets so that the particular socket to which a cable is attached may readily be determined. Likewise in the form shown in Fig. 1, similarly colored markers may be placed on the sockets and on the hinged members. 70

The preferred method of using the metering panels made up of the units described consists in mounting several of the units with 75 common bus bars 30 as above described. The bus bars 30 are then connected to meters in the usual manner and the leads from the fuse shells to the loads in suitable fashion. Each fuse then represents a single load line 80 while each bus bar 30 represents a single meter.

Fig. 6 shows such an arrangement as has just been indicated and in this figure there is shown a panel made up in any suitable 85 manner with the instrument metering board enclosed in a metal cabinet provided with a door 200 and showing at the bottom of the panel a group of the switching units indicated at 10 and these may be of either form 90 shown in Figs. 1 to 5. The bus bars cooperating therewith are shown at 30 and the power lines are shown as leading in the upper part and protected by the fusing device 100 which are preferably of the form 95 described and claimed in the previous application Ser. No. 175,173, filed March 14, 1927. The return connection is shown at 101 and is preferably located in the central portion of the panel as being the most convenient 100 place, and protected against accidental touching by means of a cover piece 102. The exposed ends of the power lines may likewise be protected as by cover 103 hinged at the top of the cabinet as at 103a. The ends 105 of bars 30 may likewise be protected by a suitable cover 104.

By this means, any load line may be easily and quickly transferred to any meter or all or any group be put on any meter without 110 any rewiring whatever, all that is necessary is to move a plug 64 or a contact member 41 to make contact with the bar 30 connected to the particular meter.

While only one group of the blocks 10 with 115 six meter bus bars has been shown it is of course obvious that two or more groups may be used and any number of bars provided for. It is also obvious that a less number of bars than six may be used in a single group 120 and these arrangements are in contemplation.

Panels may also be made up using the present type of device and adapted for double fusing, all of which will be obvious to 125 those skilled in the art.

Now, having described the invention and the preferred forms of embodiment thereof, it is to be understood that the said invention is to be limited not to the specific details 130

herein set forth, but only by the scope of the claim which follows.

I claim:—

A metering panel section including a base having on its under surface parallel conductors extending transversely of the base and having on its upper surface a plurality of conductors extending longitudinally of the base, a plurality of posts extending upwardly from and individually connected to said first named conductors in apertures passing through said base, a plurality of transversely extending closely adjacent movable connectors constructed to be of variable extent transversely of the base and including contact means adapted to be contactingly engaged with any one of the second named conductors, as desired, and a plurality of closely adjacent individual guard members for and interlocked with individual ones of the connectors, all of the members being disposed above and movably mounted on the base so as to be movable independently of one another and of the connectors associated therewith, each connector being interlocked with its own guard, so that it may not be disconnected from the second named conductors without previously moving away the guard member associated therewith, the guard members, when in position to prevent disconnection of their connectors, serving to guard the contact means of the latter from parts moving above the base.
